(57) **CLAIM**

The ornamental design for an nail file, as shown and described.

DESCRIPTION

FIG. 1 is a perspective view of the nail file;

FIG. 2 is a top view of the nail file;

FIG. 3 is a bottom view of the nail file;

FIG. 4 is a side view of the nail file, wherein the opposite side view is an identical mirror image;

FIG. 5 is a cross sectional view of the nail file taken across the line 5-5 of FIG. 2;

FIG. 6 is rear view of the nail file;

FIG. 7 is front view of the nail file;

FIG. 8 is a cross-sectional view of the nail file taken across the line 8-8 of FIG. 2;

FIG. 9 is a cross-sectional view of the nail file taken across the line 9-9 of FIG. 2;

FIG. 10 is a cross-sectional view of the nail file taken across the line 10-10 of FIG. 2; and,

FIG. 11 is a cross-sectional view of the nail file taken across the line 11-11 of FIG. 2.

The dash-dot broken lines in FIG. 2 indicate the plane upon which the sectional view is taken and form no part of the claimed design.

1 Claim, 4 Drawing Sheets
